United States Patent Office

Des. 197,215
Patented Dec. 31, 1963

197,215

TELEPHONE BOOTH UNIT

Henry Dreyfuss, South Pasadena, Calif., assignor to Bell Telephone Laboratories, Incorporated, New York, N.Y., a corporation of New York

Filed Nov. 5, 1962, Ser. No. 72,371

Term of patent 14 years

(Cl. D13—1)

F/G. 1

F/G. 3

F/G. 2

FIG. 1 is a perspective view of a telephone booth unit showing my new design;

FIG. 2 is a plan view thereof; and

FIG. 3 is a side elevational view thereof.

The broken line showing of the telephones in FIGS. 1 and 3 are for illustrative purposes only.

I claim:

The ornamental design for a telephone booth unit, as shown and described.
